STETHOSCOPE HEAD

Gustav F. Machlup and David Littmann, Belmont, Mass., assignors to Minnesota Mining and Manufacturing Company, Maplewood, Minn., a corporation of Delaware

Filed June 26, 1968, Ser. No. 12,515

Term of patent 14 years

Int. Cl. D24—03

U.S. Cl. D83—12

FIG. 1

FIG. 2

FIG. 3

FIG. 1 is a side elevational view of a stethoscope head embodying our invention;

FIG. 2 is a top plan view of the chestpiece shown in FIG. 1;

FIG. 3 is a cross-sectional view taken along the line 3—3 of FIG. 2; and

FIG. 4 is a bottom plan view of the stethoscope head shown in FIG. 1.

We claim:

The ornamental design for a stethoscope head, as shown.
